DENTAL CASTING

Hyman Freedman, New York, N. Y.

Application June 12, 1945, Serial No. 598,953

3 Claims. (Cl. 22—162)

1

This invention relates to the art of making castings of metals generally and, more particularly, to the art of casting dental fillings.

One object of the invention is the provision of a method and means for making such castings whereby a considerable amount of labor such as cutting and grinding is saved in the production of such castings.

Another object of the invention is to provide such method and means which will prevent the formation of unnecessary projections at the top of the casting thus saving a considerable amount of precious metal.

Other objects and advantages will appear as the nature of the improvements is better understood, the invention consisting substantially in the novel arrangements and co-relation of parts herein fully described and illustrated in the accompanying drawings, wherein similar reference characters are used to describe corresponding parts throughout the several views, and then finally pointed out and defined in the appended claims.

The disclosure made the basis of exemplifying the present invention suggests a practical embodiment thereof, but the invention is not to be restricted to the exact details of this disclosure, and the latter therefore, is to be understood from an illustrative, rather than a restrictive standpoint.

In accordance with a preferred form of the present invention, the device comprises a hollow tubular sprue which may have tapering sides at one end thereof, the sprue being preferably provided with a pin or similar article for insertion into a wax pattern for removal of same from the dental cavity, the tapering sides of the sprue acting to form a frangible area in the finished casting in a manner which will be hereafter described.

Figure 1 is a front view in elevation, at an enlarged scale of the sprue and pin;

Figure 2 is a longitudinal section showing the pin as being inserted into a wax filled cavity;

Figure 3 is a sectional view through a mold showing same as being provided with an opening having tapering sides left by the sprue;

Figure 4 is a side view in elevation of a modified form of the sprue;

Figure 5 is a view looking from the right of Figure 4;

Figure 6 is a sectional view through a mold formed with the use of the modified sprue;

Figure 7 is a sectional view taken on line 7—7 of Figure 6, and

2

Figure 8 is a side view of a dental filling showing a strip of mica or other similar material left in the mold by the sprue and imbedded in the casting so as to provide a frangible area for the easy removal of the cast sprue or projection at the top of the casting.

In the waxing up method for making wax patterns now commonly employed, a heated pin or other similar holder is inserted into the wax pattern. During said operation the melted wax tends to flow onto the holder and form therewith an irregular fillet-like juncture. As a result of this piling up, the same irregular formation will be transferred to the mold and finally to the casting, thus necessitating a great amount of labor in the removal of same and also causing a waste of the precious metal.

It is to obviate these undesirable features that the present improved method and means of casting dental and other fillings has been perfected.

Referring now to the drawings in detail and, more particularly, to Figures 1, 2 and 3, the numeral 10 indicates a preferably hollow tubular sprue provided with tapering side portions 11 at the bottom thereof. The bottom of the sprue at the sides 11 may be provided with short notches, cuts or slots 12. The sprue may be provided with short pins or projections 12a. A pin 13 having a shank 14 and a head 15 is adapted to pass through the inner bore 16 of the sprue. The contour of the shank 14 may be of somewhat irregular and corrugated formation and end in a somewhat bent point 17.

In practice the sprue 10 is placed in the best possible position over the wax pattern 18 shown in dot and dash lines, Figure 2, only lightly engaging same. At that time the wax will enter the slots 12. The operator while holding the sprue between the thumb and second finger, applies pressure to the head 15 by the forefinger causing the point 17 to be pushed into the wax pattern.

The somewhat hooked formation of the point 17 will facilitate the ready removal of the wax pattern from the cavity of the tooth 19 being operated upon without appreciable alteration of the surface of the pattern.

After the removal of the wax pattern from the cavity, a mold 20 may be formed in the usual manner by pouring investment material about the pattern.

The sprue 10 and pin 13 may be pulled out of the mold, and the wax pattern heated and evaporated through the opening 21 at the top of the

mold formed throughout its greater length by the tapering sides 11 of the sprue.

When casting the filling or other object, the molten metal is poured into the mold through the opening 21 and after filling the mold cavity 22, the rising material will produce a cast sprue in the opening with a substantially reduced portion corresponding to the section 24 which at its juncture with the top of the filling forms a frangible area due to which the cast sprue 23 10 may be easily broken off directly at the casting after the removal of the casting from the mold.

It will be seen that due to the piercing technique herein employed, no unsightly unwanted fillet formation is possible about the juncture of the casting and cast sprue 23. This technique 15 virtually preserves the original shape of the wax pattern at the juncture of pattern and cast sprue. It will readily be understood that a fillet formation at the base of the sprue 23 makes it impossible to break same off at that point with the consequent result that a great deal of time and labor is spent in sawing same off and then grinding the surface smooth, as well as guessing at the correct form of the surface. Likewise a considerable amount of metal is saved by the omission of the said sawing and grinding operations.

In the modified form of the invention shown in Figures 4, 5, 6, 7 and 8, there is provided a sprue 25 having a spring clip 26 adapted to hold a strip of mica 27 or other similar material. The said mica strip may be bent at right angles, the vertical wall 28 thereof being held between the outer surface of the sprue and the clip 26 while the horizontal wall 29 is held laterally between a pair of pins or prongs 30 at the bottom of the sprue.

In this modified form of the invention the prongs 30 are inserted into the wax pattern which pattern is then extracted from the tooth cavity and the investment material is poured to form the mold 20a. When the mold is thus formed the mica strip becomes imbedded along its vertical edges 31 in the investment material. The sprue is then withdrawn from the mold disengaging itself from the mica strip which remains imbedded in the orifice 21a. Then the wax pattern is evaporated from the mold. The flap 29 of the mica strip 27 forms a hinge with the vertical portion 28 and extends between the mold cavity 32 and the passage 21a directly above the mold cavity.

When casting the filling 33 the molten metal is poured through the passage 21a and will push downwardly the flap 29 of the mica strip 27. The level of the molten metal in the mold cavity 32 will rise gradually and will move the flap 29 back to its horizontal position. After filling the mold cavity 32, the molten metal will fill the opening or orifice 21a and will form a cast sprue 34 in the bottom of which the flap 29 will be 60 imbedded in such a manner as to provide a very weak area 35 at which area the cast sprue 34 may be broken off without any great exertion.

From the foregoing it will be seen that in the first form of the invention a progressively reduced area is provided at the juncture of the casting and its sprue cast by means of tapering sides or progressively diminishing diameters of the wax pattern-holding sprue, with the weakest breaking point directly at the surface of the casting; in the modified form of the invention the mica strip acts to form the weak area. Thus, in both instances, there is provided a weakened or frangible area directly at the surface of the casting at which the cast sprue may be quickly, easily and effectively removed.

While the invention has been shown and described as relating to dental fillings, it is to be understood that the invention may as readily be utilized in the production of a great variety of other castings without departing from the scope of the appended claims.

What is claimed is:

1. For use in combination with a mold for casting dental fillings or other objects, a hollow sprue having opposed tapering sides near the bottom thereof and round surfaces joining said tapering sides, and a pin passing longitudinally through the sprue and adapted to be inserted into a wax pattern, the sprue having notches at the bottom thereof for the admission of pattern material, and further having two diametrically disposed pins for holding the pattern material, the tapering sides being adapted to form a restricted area in the mold at the juncture of the cavity in the mold formed by the pattern and the opening by the sprue.
2. For use in forming a mold for casting various articles, a casting adjunct comprising a pattern-holding hollow sprue tapering at one end to a thin, flat edge, said edge having pointed projections at opposite ends of said edge.
3. For use in forming a mold for casting various articles, a casting adjunct comprising a pattern-holding hollow sprue, the pattern-engaging end being tapered at least on one side and having at least two projections depending from the extremity of the pattern-engaging end.
